US00D661742S

(12) **United States Design Patent**
Clark et al.

(10) **Patent No.:** US D661,742 S
(45) **Date of Patent:** ** Jun. 12, 2012

(54) **LABEL**

(75) Inventors: **Paul Aaron Clark**, Youngstown, NY (US); **Bryan Scott Poltilove**, Clarksville, MD (US); **Brian Michael Buxton**, Grand Island, NY (US)

(73) Assignee: **Life Technologies Corporation**, Carlsbad, CA (US)

(**) Term: **14 Years**

(21) Appl. No.: **29/392,986**

(22) Filed: **May 27, 2011**

(51) LOC (9) Cl. **19-08**

(52) U.S. Cl. **D20/27**

(58) **Field of Classification Search** D20/10, D20/11, 19, 22–28, 40, 99; 40/5, 6, 124.01–124.11, 40/124.11–124.19, 124.191, 299.01, 309, 40/312, 313, 359, 360, 625; D9/433, 457; D19/1, 9–11; 206/308.1; 220/694; 283/56, 283/71, 81, 101, 105; 428/40.1, 42.1–42.3, 428/43, 914; 493/216; 235/492

(57) **CLAIM**

The ornamental design for a label, as shown and described.

DESCRIPTION

This application is related to U.S. design patent application titled "Label" filed on the same date with the same inventors under Ser. No. 29/392,987.

FIG. 1 is a view of a first embodiment of a label according to our new design; and,

FIG. 2 is a view of a second embodiment of a label according to our new design.

The backside (not pictured) of the label as well as the portions of the label depicted in broken lines are not part of the claimed design.

The gibco trademark shown in broken lines is a registered trademark of Life Technologies Corporation and forms no part of the claimed design. The stylized life technologies trademark shown in broken lines is a trademark of Life Technologies Corporation and forms no part of the claimed design.

1 Claim, 2 Drawing Sheets

FIG. 1

FIG. 2
